(57) **CLAIM**

The ornamental design for a pet carrier, as shown and described.

DESCRIPTION

FIG. 1 is a left, front and top perspective view of a pet carrier showing my new design;

FIG. 2 is a right, rear and bottom perspective view;

FIG. 3 is a left view thereof;

FIG. 4 is a right view thereof;

FIG. 5 is a rear elevational view thereof;

FIG. 6 is a front elevational view thereof;

FIG. 7 is a top plan view thereof;

FIG. 8 is a bottom plan view thereof;

FIG. 9 is another left, front and top perspective view thereof, showing the left side cover rolled up;

FIG. 10 is another left view thereof, showing the left side cover rolled up;

FIG. 11 is an enlarged view of a portion labeled as 11 on FIG. 1; and,

FIG. 12 is an enlarged view of a portion labeled as 12 on FIG. 2.

The long dash—short dash broken lines depict enlargement boundaries that form no part of the claim.

1 Claim, 12 Drawing Sheets
